SHOPPING CENTER

Allan McNab, New York, N. Y., assignor to Allan McNab & Associates Inc., New York, N. Y., a corporation of New York

Application October 22, 1948, Serial No. 149,248

Term of patent 3½ years

(Cl. D13—1)

To all whom it may concern:

Be it known that I, Allan McNab, a citizen of the United States, and a resident of New York, in the county of New York, State of New York, have invented a new, original, and ornamental Design for Shopping Center, of which the following is a specification, reference being had to the accompanying drawings, forming part thereof.

In the drawings:

I claim:
The ornamental design for a shopping center, as shown.

ALLAN McNAB.
